(57) **CLAIM**

The ornamental design for a rifle scope, as shown and described.

DESCRIPTION

The file of this patent contains at least one drawing/photograph executed in color. Copies of this patent with color drawing(s)/photograph(s) will be provided by the Office upon request and payment of the necessary fee.

Fig. 1.1 is a perspective view of a rifle scope showing my new design;

Fig. 1.2 is a top plan view thereof;

Fig. 1.3 is a bottom plan view thereof;

Fig. 1.4 is a front elevation view thereof;

Fig. 1.5 is a rear elevation view thereof;

Fig. 1.6 is a right side elevation view thereof; and

Fig. 1.7 is a left side elevation thereof.

The broken line shows a boundary between claimed and unclaimed features of the rifle scope. The portion enclosed by the boundary line forms no part of the claimed design. The dark background in all figures is included for the purpose of providing contrast and forms no part of the claimed design.
